UNITED STATES PATENT OFFICE

2,459,384

MOTOR-DRIVEN TOOL MECHANISM

Thor H. Ljunggren, Charlestown, N. H., assignor
to Bryant Chucking Grinder Company, Springfield, Vt., a corporation of Vermont

Application September 11, 1943, Serial No. 501,949

3 Claims. (Cl. 172—36)

1

This invention relates to motor driven tools or work holders and while not restricted thereto, it has been developed more particularly in connection with high speed small diameter grinding wheels or similar tools driven by high frequency induction or repulsion electric motors. For such high speed spindles, it is important to employ as few bearings as possible in order to avoid bearing friction. It is also important that the motor rotor be accurately concentric with the spindle. It may also be desirable to employ grinding wheels or other tools of different contours or cutting qualities or work holders of different types from time to time in the same machine and to change from one to another quickly and in connection with tools with a single chucking or other support of the work.

An object of the present invention, therefore, is to reduce to a minimum the number of bearings required to support the motor rotor and the spindle.

A further object is to facilitate the rapid change from one to another tool or other device.

A still further object is to provide for permanent alignment of the motor rotor and the spindle.

To these ends the motor rotor and the spindle are made as one and the same member, and this member, together with a tool mechanism and the bearings for the spindle, are made as a single unitary structure which may be detachably associated with a motor stator and interchangeable with similar units carrying mechanism for holding tools of other shape, cutting, or other qualities, or for supporting work holders, or other devices.

For a more complete understanding of this invention reference may be had to the accompanying drawings in which

Figure 1 is a view partly in side elevation and partly in section of a grinding wheel spindle and its mounting, embodying the invention.

Figure 2 is a front elevation of the same.

Figures 3 and 4 are side elevations of wheel and rotor units of different forms which may be interchanged for the unit shown in Figures 1 and 2.

Figure 5 is a view somewhat similar to Figure 1, but showing a modified unit and mounting.

Figure 6 is a detail sectional view on line 6—6 of Figure 5.

Figures 7 and 8 are side elevations of units of different forms which may be interchangeably substituted for the unit shown in Figure 5.

Referring first to Figure 1, at 1 is indicated a

portion of a machine bed to which is clamped, as by a clamping bar 2, and screws 3, the base portion 4 of a motor casing 5 within which is secured the stator 6 comprising a core and frame of a motor, preferably of the induction or repulsion type, and preferably also one capable of being excited with high frequency alternating current. The rotor 7 for this motor is fixedly secured to a spindle 8 mounted for rotation within a bearing casing 9 through which it extends and on the opposite side of which it has means of any suitable description for securing a tool thereto. As shown this tool is a grinding wheel 10. The bearing casing 9 may have any suitable bearing arrangement therein and may, for example, comprise a pair of spaced radial and axial thrust ballbearings, though any other desired type of bearing suitable for the particular type of tool may be employed. This bearing casing, as shown, has at its inner end an outwardly extending marginal flange 15 and an axially extending flange 11. These flanges 15 and 11 are arranged to engage the end wall portion 12 and the inner face portion 13, respectively, of the motor casing 5, and screws 14 may be employed to secure the bearing casing 9 to the motor casing 5, as shown, with the rotor 7 in operative relation to the stator 6.

In Figures 3 and 4 are illustrated other tool units, each comprising a bearing casing 9a and 9b within which is journaled a spindle 8 on the inner end of which is mounted the rotor 7, and on the outer end of which a different tool is carried. In each instance a grinding wheel is shown as the tool, the grinding wheels 10a and 10b of Figures 3 and 4, respectively, being of different size or cutting quality, or differing in other respects from the wheel 10 shown in Figures 1 and 2. Each of these units in its bearing casing 9a or 9b is provided with flanges 15 and 11 identical in size and arrangement with the similarly numbered flanges of the unit shown in Figure 1, so that any of these units may be interchangeably associated with the stator 6 of the motor casing and with the machine support which carries this casing. It will thus be seen that the rotors in all cases are relatively permanently associated with their spindles so that their coaxial relation therewith may be assured and that the entire bearings for the spindle and the motor rotor are contained within the bearing casing 9, 9a or 9b, so that the number of bearings may be reduced to a minimum, which is desirable for high speed operation. Likewise, the tools or work holders which may be supported by the several

spindles of the various units may be of different shapes, cutting qualities, or otherwise differ, but all can be employed with the same motor stator.

In Figures 5 to 8, a modification is shown in which the stator support 100 is provided with suitable flanges 101 to which the casing 102 of the motor stator may be secured as by screws 103, the particular stator shown having the windings 104 and being closed over at its outer end by the cover 105. The support 100 also has a split bearing portion at 110, the parts of which may be clamped together as by the screws 111 and into clamping relation to a bearing casing 112 of cylindrical exterior. This bearing casing may have journaled therethrough the tool spindle 115 carrying the motor rotor 116 at its inner end and a tool, such as a grinding wheel 117, at its outer end.

Other units comprising the cylindrical bearing casings 112a and 112b as shown in Figures 7 and 8 and having journaled therethrough their own spindles 115, together with rotors 116 at their inner ends and tools such as grinding wheels as 117a and 117b at their opposite ends, may then be interchangeably associated in the split bearing of the support 100, with the motor rotor carried thereby in cooperative relation to the stator secured to the support 100.

From the foregoing description of certain embodiments of this invention, it will be understood by those skilled in the art that various other arrangements of interchangeable units, each comprising a bearing casing, a spindle journaled therethrough, and a rotor at one end and a tool or a work holder at the other, may be employed, all interchangeable with other units having different tools or holders carried by their spindles.

It is also evident that other changes and modifications might be made without departing from the spirit or scope of this invention.

I claim:

1. In combination, a unit comprising a spindle, a motor rotor on one end of said spindle, a device at the opposite end of said spindle, and a spindle

bearing casing between said rotor and device and within which said spindle is journaled, a support, a motor stator comprising a core and frame carried by said support, and means for removably securing said unit with the motor rotor in operative relation to said stator.

5 2. In combination, a unit comprising a spindle, a motor rotor on one end of said spindle, a device at the opposite end of said spindle, and a spindle bearing casing between said rotor and device and within which said spindle is journaled, a support, a motor stator comprising a core and frame carried by said support, said casing and support having flanges mating when said rotor is in operative relation to said stator, and removable means for securing said flanges together.

10 3. In combination, a unit comprising a spindle, a motor rotor on one end of said spindle, a device at the opposite end of said spindle, and a spindle bearing casing between said rotor and device and within which said spindle is journaled, a support, a motor stator carried by said support, said casing being cylindrical in contour, and said support having a clamping portion for securing said cylindrical casing, and clamping said unit in position with its rotor in operative relation to said stator.

15 THOR H. LJUNGGREN.
